UNITED STATES PATENT OFFICE

147,463

DESIGN FOR AN ADJUSTABLE LOUNGE
CHAIR

Frank J. Luketa, Seattle, Wash.

Application March 26, 1946, Serial No. 127,958

Term of patent 14 years

(Cl. D15—1)

To all whom it may concern:

Be it known that I, Frank J. Luketa, a citizen of the United States of America, residing at Seattle, in the county of King and State of Washington, have invented a new, original, and ornamental Design for an Adjustable Lounge Chair, of which the following is a specification, reference being had to the accompanying drawing, forming part thereof.

parts in the same positions of adjustment, both showing my new design.

I claim:

The ornamental design for an adjustable lounge chair, substantially as shown.

FRANK J. LUKETA.
